FIG. 5

FIG. 1 is a perspective view of a storage box showing our new design;

FIG. 2 is a perspective view thereof with the lid raised showing the front side, the back side being the same as the front side shown in FIG. 3;

FIG. 3 is a front elevational view thereof;

FIG. 4 is a side elevational view thereof, the other side being a mirror image of the side shown in FIG. 4; and FIG. 5 is a bottom plan view thereof.

We claim:

The ornamental design for a storage box, as shown and described.
